UNITED STATES PATENT OFFICE.

JONATHAN HARRIS, OF GRAND LEDGE, MICHIGAN.

CURTAIN-ROLLER FIXTURE.

SPECIFICATION forming part of Letters Patent No. 296,003, dated April 1, 1884.

Application filed December 19, 1883. (No model.)

To all whom it may concern:

Be it known that I, JONATHAN HARRIS, of Grand Ledge, in the county of Eaton and State of Michigan, have invented new and useful Improvements in Curtain-Roller Fixtures; and I do hereby declare that the following is a full, clear, and exact description thereof, reference being had to the accompanying drawings, which form a part of this specification.

10 This invention relates to certain new and useful improvements in curtain-roller supports, and is especially designed as an improvement upon the invention described in Letters Patent No. 274,191, issued to me March 20, 1883.

15 The invention consists in the peculiar construction and operation of a supporting hook and bearing, by means of which one end of the roller is supported, and which furnishes a stop 20 to arrest the curtain-cord at any desired point.

25 Figure 1 is an elevation of the curtain and fixtures, the curtain being extended to cover the whole window. Fig. 2 is a detached perspective of the locking-hook.

30 In the accompanying drawings, which form a part of this specification, A represents the curtain, B the roller, C the hook which supports one end of the curtain, and D the cord by means of which the roller is rotated to wind or unwind the curtain, these parts being constructed, arranged, and operating as described in my aforesaid Letters Patent.

35 E is the locking-hook shown in Fig. 2 in two modifications, exactly alike, except in the loop or ring by means of which it is attached to the roller. This hook E is made from one piece of wire, bent so as to form a loop, a, which is designed to engage with one of the 40 bolts or hooks F, which are screwed into the

window-frame. Below this loop a is formed another loop, b, which may be larger or smaller, the larger allowing it to be sleeved upon the end of the roller and form a bearing therefor, and the smaller one engaged with the end of 45 the roller by means of a screw, by means of which the roller rotates in this bearing. The wire, after forming the loop b, is bent forward, and then at right angles, and then downwardly and back upon itself, so as to form the loop c, 50 terminating in a V-shaped slot, d, formed by the converging portions of the wire.

55 In practice, when it is desired to roll up the curtain from the position shown in the drawings, it is only necessary to pull upon the cord, and when the bottom of the curtain is at the desired height engage the cord in the V-shaped slot by the slight movement of the hand to the front or right and left. To again change the position of the bottom of the curtain simply 60 requires a slight pull upon the cord, which detaches it from its engagement and allows it to play freely through the lower part of the loop.

What I claim as my invention is—

1. In combination with a curtain roller and 65 cord, a wire support forming a bearing which carries the end of said roller, supports the same from a fixed point, and furnishes a spring locking loop and slot, substantially as and for the purposes described.

2. In combination with a curtain cord and 70 roller, the locking-support E, bent from one piece of wire, forming the loops b c and the slot d, substantially as and for the purposes described.

JONATHAN HARRIS.
